UNITED STATES PATENT OFFICE.

JOSEPH C. MCKENZIE, OF ADRIAN, MICHIGAN.

CUTTING-TABLE FOR TILE AND BRICK MACHINES.

SPECIFICATION forming part of Letters Patent No. 291,616, dated January 8, 1884.

Application filed December 11, 1881. (No model.)

To all whom it may concern:

Be it known that I, JOSEPH C. MCKENZIE, a citizen of the United States of America, residing at Adrian, in the county of Lenawee 5 and State of Michigan, have invented certain new and useful Improvements in Cutting-Tables for Tile and Brick Machines; and I do hereby declare the following to be a full, clear, and exact description of the invention, such

as will enable others skilled in the art to which it appertains to make and use the same, reference being had to the accompanying drawings, and to letters or figures of reference marked thereon, which form a part of this specification, and in which—

Figure 1 is a side elevation of the table in position to receive the column of clay. Fig. 2 is a top plan view. Fig. 3 is a side elevation of the table with hinged section raised 20 and a portion of tile on the pallet-board in an upright position.

My invention has for its object to provide a cutting-table for tile and brick machines, especially for screw-machines, by which the section of tile cut from the column of clay can be raised from a horizontal to a vertical position; and it consists in the arrangement and combination of certain parts, which I will now proceed to describe.

Similar letters of reference indicate like parts.

Referring to the drawings, A is the frame of the table, mounted upon the wheels B, which run on the track C, said track being placed 35 so that the end C' will be just under the mouth of the machine.

D are the horizontal rollers upon which the column of clay rests as it is forced from the machine.

E E E E are adjustable supports for the side rollers or guides, F, and are secured to the top of the frame of the table, and are adjustable by means of a slot, e, and screw e', to suit any size tile-pipe.

F are the upright side rollers or guides, secured to said adjustable supports E.

G is the cutting-wire.

H is the movable section of the table, hinged at h h, and provided with handles a a, and bar 50 c, and projections d d for holding the pallet-

board I in place, when the section H is in a horizontal position, and supporting it when section H is raised to a vertical position.

I is a removable pallet-board, upon which the tile rests when cut off, and the section H 55 is in an upright position.

K is the stationary section of the table, which receives the column of clay and supports it while the section H is raised.

L is the mouth of the tile or brick machine. 60

M is a column of clay, and N a portion of tile cut off and raised to an upright position.

The operation of my table is as follows: The table is placed in position so that the receiving end is at the mouth of the machine. The 65 machine is started and the column of clay passes out over the rollers D, and between the side roller or guides, F, until one end of said column reaches the pallet-board I. The cutting-wire is then dropped, and the portion of 70 tile on the movable section of the table cut off from the column of clay. The table is then pushed forward away from the machine to the end C' of the track. The section H is raised to a vertical position, and the pallet- 75 board I removed with the tile resting on it in an upright position. The section H is then dropped to a horizontal position, and the table pushed back to the machine, a new pallet-board put in place, and the movable section 80 is ready to receive another portion of tile.

Having thus fully described my invention, I claim—

1. A cutting table for a tile-machine, consisting, essentially, of a frame traveling upon a 85 track, said frame being provided with a stationary section and a hinged section, all constructed and operating to the end that the table may be moved forward a limited distance, unloaded, and returned beneath the constantly progressing column of clay.

2. In a cutting-table for a tile or brick machine, the combination of the frame A, stationary section K, hinged section H, wheels B, and track C, substantially as shown and described.

3. The combination of the frame A, stationary section K, hinged section H, pallet-board I, wheels B, and track C, substantially as shown and described.

4. In a cutting-table for a tile or brick machine, the combination of the vertical rollers or guides F, and adjustable supports E, with the frame A, whereby said side rollers or guides 5 can be adjusted to suit any size of tile-pipe, substantially as shown and described.

5. The combination of the frame A, stationary section K, hinged section H, pallet-board I, horizontal rollers D, side rollers, F, and adjustable supports E, cutting-wire G, wheels B, 10 and track C, substantially as and for the purpose shown and described.

6. In a cutting-table for a tile-machine, the combination, with a frame traveling upon a track, and provided with a stationary and a 15 hinged section, of a cutter arranged at one end of the hinged section, substantially as shown and described.

In testimony whereof I affix my signature in presence of two witnesses.

JOSEPH C. MCKENZIE.
